[57] CLAIM

The ornamental design for a combination chair and drawer, as shown and described.

DESCRIPTION

FIG. 1 is a perspective view of a combination chair and drawer showing my new design, illustrating the drawer thereof in a closed configuration.

FIG. 2 is a perspective view thereof, illustrating the drawer in an open configuration.

FIG. 3 is a front elevational view thereof illustrating the drawer in a closed configuration.

FIG. 4 is a left side elevational view thereof.

FIG. 5 is a right side elevational view thereof.

FIG. 6 is a top plan view thereof.

FIG. 7 is a rear elevational view thereof.

FIG. 8 is a bottom plan view thereof.

FIG. 1

FIG. 2

FIG. 3

FIG. 4

FIG. 5

FIG. 6

FIG. 7

FIG. 8
